UNITED STATES PATENT OFFICE.

GEORGE POLL, OF NEW YORK, N. Y.

DESIGN FOR A TABLE.

55,884.

Specification for Design.

Patented July 20, 1920.

Application filed April 9, 1920. Serial No. 372,683. Term of patent 7 years.

To all whom it may concern:

Be it known that I, GEORGE POLL, a citizen of the United States, and a resident of the city of New York, Ridgewood, borough of Queens, in the county of Queens and State of New York, have invented a new, original, and ornamental Design for Tables, of which the following is a specification,

reference being had to the accompanying drawings, forming part thereof.

The figure is a perspective view of a table showing my new design.

I claim:

The ornamental design for a table, as shown.

GEORGE POLL.
